UNITED STATES PATENT OFFICE.

EDWARD H. BERG, OF MINNEAPOLIS, MINNESOTA.

ADJUSTABLE CASTER-CUP.

1,389,572.

Specification of Letters Patent. Patented Sept. 6, 1921.

Application filed October 22, 1920. Serial No. 418,763.

To all whom it may concern:

Be it known that I, EDWARD H. BERG, a citizen of the United States, residing at Minneapolis, in the county of Hennepin and State of Minnesota, have invented certain new and useful Improvements in Adjustable Caster-Cups; and I do hereby declare the following to be a full, clear, and exact description of the invention, such as will enable others skilled in the art to which it appertains to make and use the same.

This invention relates to a caster cup and is particularly designed to provide an adjustable support for the casters used on furniture legs or supports. It is well known that frequently, only three of the legs will support a piece of furniture, or other article, leaving one or more legs out of contact with the floor or other supporting surface. This results in great and unequal stresses being placed upon the furniture, especially if the same has considerable weight. It often happens that articles of furniture, such as heavy dressers, chiffonniers, or phonograph cabinets which are composed of sectional and veneered parts, are seriously cracked and damaged on account of these stresses set up by the imperfect support.

One object of this invention is to provide a caster support, by means of which all the legs supporting a phonograph cabinet, or other heavy piece of furniture, may equally bear the weight thereof.

It is another object of the invention to provide such a device of great simplicity which can be easily made and easily applied to its intended use.

Other objects of the invention will appear as the description proceeds in connection with the accompanying drawings in which like reference characters refer to the same parts throughout the different views, and in which—

Figure 1 is a central vertical section through the caster cup showing a portion of the supporting leg and caster supported thereby;

Fig. 2 is a central vertical section of the leg piece of an article of furniture, the caster thereon and the supporting cup therefor;

Fig. 3 is a similar vertical section showing a different type of caster; and

Fig. 4 is a view showing an adjustable caster.

Referring to the drawings, the numeral 1, Fig. 1, represents a supporting leg of an

article of furniture, or other object having at its lower end the usual caster comprising the support 2 and the roller or ball 3. This caster is supported upon a cylindrical member 4 having a closed upper portion 5 formed as a spherical or semi-spherical receptacle. A cylindrical member 4 is open at its other end and has threads 6 formed on its interior. These threads are adapted to engage with similar threads 7 formed on the exterior of a supporting cup member 8 closed at its bottom to form a base 9. A piece of felt, or similar material 10 is glued or otherwise secured to the bottom of member 8 to form a support which will not mar or scratch the finished surface of a floor, or other supporting means.

In Fig. 2, a similar caster support is shown, but the caster member 2^a, in this figure, is internally threaded to be screwed upon a sleeve 11 similarly threaded, and which is tightly secured to the leg member 1.

In Fig. 3 is shown a caster support similar to those shown in Figs. 1 and 2, but a different type of caster is illustrated. This particular caster comprises a wheel 12 carried on a pivot 13 extending between depending arms 14 which are carried by the sleeve 2. As shown in Fig. 2, the sleeve 2 also engages the threaded sleeve 11 rigidly secured to the leg member 1.

Fig. 4 discloses an adjustable type of caster similar to that shown in Fig. 2. The ball 3 of which is shown as in direct contact with the floor, or other supporting surface.

The use or operation of the device will be readily understood. The caster supporting member will be inserted under the casters on the various legs of the article to be supported. If one or more of the legs are not in contact with the support the sleeve 4 will be turned upon the member 8 and suitably adjusted so that the caster will firmly bear upon the same and be supported thereby. In this manner, the weight of the piece of furniture, or other object, can be made to be equally distributed on the various legs. The setting up of damaging stresses in the supported object is thus avoided.

While any suitable material may be used in making the device, it can be cheaply and ornamentally made of steel having its surface oxidized. The felt or other material on the bottom of the support will prevent marring of the supporting surface and such supporting surface will also not be marred by direct contact with the caster. The sup-

ported object will, on the contrary, be efficiently and firmly supported in one position. The size of the device will, of course, be made to best suit the size of the supporting legs and that of the furniture.

It will, of course, be understood that various changes in form, design and details of the device may be made without departing from the scope of applicant's invention, 10 which, generally stated, consists of the matter shown and described and set forth in the appended claims.

What is claimed is:

1. A caster support having in combination 15 an open ended cup member having its exterior surface threaded, a layer of soft material secured to the bottom of said cup member, and an inverted cup shaped member having its upper exterior surface con- 20 cave and its side portion interiorly threaded to engage the threaded sides of the first mentioned cup member.
2. A caster support having in combination 25 a base member and a caster supporting member adjustably mounted thereon, said supporting member having its upper surface formed as a concave caster supporting receptacle.
3. A caster support having in combination

a cylindrical base member having screw 30 threads on its exterior surface, a supporting sleeve having screw threads on its interior surface adapted to engage with the threads on said base member, and having its upper end formed as a caster support.

4. A caster support having in combination 35 a base member formed as a hollow cup, a felt member of equal diameter secured to the lower face thereof, the sides of the cup having screw threads formed thereon and an inverted cup member having screw threads 40 on its interior adapted to engage the threads on said first mentioned cup member, having its upper surface formed with a semi-spherical cavity.

5. The combination with a leg member 45 and caster carried thereby, of a caster supporting member comprising a base formed as a cylindrical cup, a layer of felt secured to the bottom thereof, screw threads formed on the exterior of the cup, and a cylindrical member having a closed top portion and having screw threads on its interior adapted to engage said threads on the cup, the said top portion being formed as a semi-spherical receptacle to support the caster.

In testimony whereof I affix my signature
EDWARD H. BERG.
